CENTRALIZED TRAFFIC CONTROLLING SYSTEM

George J. Johaneck, Rochester, N. Y., assignor to General Railway Signal Company, Rochester, N. Y.

Application April 30, 1931, Serial No. 533,899

34 Claims.

(Cl. 246—3)

This invention relates to centralized traffic controlling systems for railroads, and more particularly pertains to a system of the type employing direct line wire control as contrasted with a system of the selector type.

In accordance with this invention, it is proposed to govern a track switch over a polarized control circuit, and to govern the signals associated with such track switch over another polarized control circuit. It is further proposed to employ a third line circuit with the above mentioned control circuits in a manner to indicate in a control office the locked or unlocked condition of the track switch together with its normal or reverse position, and the clear or stop condition of the associated signals together with the direction of traffic established when a particular signal is cleared. This third line circuit is employed alternately, in accordance with the energized or deenergized condition of the signal control circuit, to transmit the switch and signal indications respectively with such indications being made distinctive in each case by the polarity applied to the circuit from a battery or other suitable source located at the track switch.

Other objects, purposes and characteristic features of the present invention will be in part obvious from the accompanying drawings and in part pointed out as the description of the invention progresses.

In describing the invention in detail, reference will be made to the accompanying drawings which illustrate in a diagrammatic manner one specific embodiment of the present invention.

Although the present invention may be applied to double track railroads, interlocking plants and various other track layouts, it has been specifically illustrated in the present embodiment of the invention as applied to a single track railway system having passing sidings and preferably provided with a signal system of the absolute-permissive-block type such for example as disclosed in the pending application of S. N. Wight, Ser. No. 120,423, filed July 3, 1926.

With reference to the accompanying drawings, the west end of a passing siding has been illustrated as having rails 5 connected to a main track having rails 6 by a track switch TS (see Fig. 1B). This track switch TS is preferably operated by a power driven switch machine SM which may be of any suitable type, such for example, as disclosed in the patent to W. K. Howe, Patent No. 1,466,903, dated September 4, 1923. This switch machine SM is also preferably provided with a dual control selector to permit hand operation

of the track switch, as disclosed, for example, in the pending application of W. K. Howe, Ser. No. 354,039, filed April 10, 1929, which has matured into Patent Number 1,852,573, dated April 5, 1932.

The main track adjacent the track switch TS and a portion of the side track included up to the fouling point comprises a detector track section TK provided with the usual track battery and track relay T, which section is insulated from the rest of the track by the usual insulated joints.

Traffic over the track switch TS is governed by the usual signals illustrated as signals 1 and 1A for governing traffic in an east bound direction on the main line and onto the passing siding respectively, and as signals 2 and 2A for governing traffic in a west bound direction on the main line and off the passing siding respectively.

Associated with the signals 1—1A and 2—2A are the home relays 1H and 2H respectively, these relays being of the usual polar-neutral type. The relay 1H is governed in accordance with traffic conditions east of the signals 1—1A; while the relay 2H is governed in accordance with traffic conditions west of the signals 2—2A. The control of these relays 1H and 2H need not be herein specifically pointed out, as they are controlled in the usual manner employed in absolute-permissive-block systems of the type contemplated to be employed with this invention, for example, as disclosed in the above mentioned application of S. N. Wight, Ser. No. 120,423.

Associated with the track switch TS and switch machine SM are suitable point detector contacts (not shown), such for example, as disclosed in the patent to C. S. Bushnell, Patent No. 1,517,236, dated November 25, 1924 so as to energize a switch repeating relay WP from a local source with one polarity or the other when the track switch TS is in extreme normal or extreme reverse locked positions, and so as to deenergize this relay WP whenever the track switch TS is unlocked or the switch machine SM is in operation. Such control of the relay WP is not specifically shown, as it is well understood to those skilled in the art, but is merely indicated by a dotted line extending from the track switch TS and the switch machine SM. This relay WP is of the polar-neutral type having neutral contacts which assume energized or deenergized positions dependent on energization thereof and irrespective of the polarity applied to the windings of the relay and polar contacts operated to either of two extreme polar positions in accordance with the polarity applied these polar contacts remain-

ing in such positions until a different polarity has been applied.

A relay WZ of the polar neutral type is governed from the control office, so as to govern the 5 operation of the switch machine SM. This control of the switch machine SM is indicated as being accomplished by contact J of relay WZ, it being understood that this control may be accomplished in any suitable manner with such approach locking and detector locking as may be desired.

A polar-neutral relay SZ is governed from the control office to hold the signals 1—1A and 2—2A at stop or to allow a particular signal to clear in 15 accordance with traffic conditions in advance. This relay SZ is employed to select, in cooperation with the switch repeating relay WP, one of four signal control relays G, such as relays 1G—1AG and 2G—2AG. As obvious from the 20 reference characters applied to the relays G, they are provided to control the respective signals 1—1A and 2—2A which have been illustrated as being of the color light type. These signals display red or danger indications whenever their 25 corresponding G relays are deenergized and display proceed indications, green or yellow, in accordance with traffic conditions as determined by the relays 1H and 2H when a corresponding G relay is energized. Although the control of the 30 signals has been in part illustrated and in part indicated, it is to be understood that such control may include suitable route locking, time locking, stick features and the like without departing from the present invention.

Associated with the relays 1G and 1AG is a relay 1M energized whenever these relays are deenergized; and similarly, associated with the relays 2G and 2AG is a relay 2M energized whenever these relays are deenergized.

In the central control office (see Fig. 1A), a track diagram is provided which conforms to the actual track layout in the field, being specifically illustrated in this case as the west end of a passing siding having a miniature track switch point 45 corresponding to the track switch TS and being operable to normal and reverse positions by suitable magnetic control means in accordance with the normal or reverse positions of a polar contact 8 of the switch indicating relay WIR, all of which is obvious from the drawings.

Associated with the miniature track switch TS are two control levers, a switch machine control lever SML and a signal control lever SGL. The switch machine lever SML is of the two-position 55 type operating contacts to either normal or reverse extreme positions; while the signal control lever SGL is of the three-position type operating a contact to any one of three corresponding positions.

The switch machine lever SML controls the switch machine control relay WZ in the field over a polarized line circuit including line wire 9 employed in conjunction with a common return wire. The energized or deenergized condition of the 60 control circuit thus established is repeated in the control office by a repeating relay WZR of the neutral type. Similarly, the signal control lever SGL governs the signal control relay SZ over a polarized line circuit including line wire 10 in conjunction with the common return line wire. The energized or deenergized condition of this 65 control circuit is repeated in the control office by a repeating relay SZR of the neutral type.

Two polar-neutral indicating relays WIR and 70 SIR are employed to indicate respectively the

condition of the track switch TS and the condition of the signals 1—1A and 2—2A. These indicating relays are controlled over their corresponding polarized circuits including the line wire 11 used in conjunction with the common 5 return line.

A neutral correspondence relay COR having associated therewith a correspondence indicating light CI, is employed to determine the correspondence between the switch machine control lever SML, the switch machine control relay WZ, and the switch repeating relay WP in a manner 10 as more specifically pointed out hereinafter.

Associated with the track diagram is an indicator lamp I for indicating the occupancy of the 15 detector track section TK as determined by neutral relay OS in the tower governed in accordance with the condition of the track relay T in a manner hereinafter pointed out.

Also, two indicating lamps EI and WI are employed to indicate respectively the establishment 20 of east bound or west bound traffic over the track switch TS as indicated in the control office by the relay SIR.

Both at the field location and in the control 25 office battery symbols have been employed in place of the actual connections to suitable batteries or other sources. Symbols (+) and (—) are employed to indicate connections to the positive and negative terminals of a suitable source local to 30 either the control office or the field station where thus indicated. Circuits employing these symbols always have current flowing in the same direction when closed.

A battery 15 in the control office, and a battery 16 at the field station is provided for furnishing current for the line circuits. Each of these battery sources has been provided with a center or intermediate tap connected to the common return line. The common return line 40 may or may not be employed as the common return for other associated field stations all as may be desired to meet the requirements of practice.

It is believed that further description of the 45 present invention will best set forth the characteristic features and functions of the system of this invention by considering in detail the operation of the system under certain characteristic or typical conditions.

Operation of the system

Under normal conditions the switch machine lever SML is in a normal position as illustrated, 55 and the signal lever SGL is in a central at stop position as illustrated. Thus, the control circuit for the signal control relay SZ is deenergized; while the control circuit for the switch machine control relay WZ is energized from the positive terminal of the battery 15, through wires 20 and 21, contact 22 of lever SML, wire 23, winding of relay WZR, wire 24, back contact 25 of relay SZR, control line wire 9, front contact 26 of track relay T, wire 27, winding of relay WZ, wires 28, 29 and 30, to the common return wire, and thence to the control office to the mid-point of the battery 15.

This energizing circuit for the relay WZ causes 60 its contacts to be actuated to right hand extreme positions so that the track switch TS is in a normal position for the passage of traffic over the main track. This position of the track switch TS is indicated by suitable energization 65 of the relay WP actuating its polar contacts to 70

right hand extreme positions and neutral contacts to energized positions.

As the relays WP and WZ are in correspondence, an energizing circuit is completed for the switch indicating relay WIR in the control office from the positive terminal of the battery 16, through wires 31 and 32, contact 33 of relay WZ in a right hand position, wire 34, contact 35 of relay WP in a right hand position, wire 36, front contact 37 of relay WP, wire 38, back contact 39 of relay SZ, indicating line wire 11, back contact 40 of relay SZR, wire 41, windings of relay WIR, wires 42 and 43, to the common return wire, and thence to the field location, wires 30 and 44, to the mid-point of battery 16. This energization of the relay WIR actuates its neutral contact to an energized position and its polar contacts to right hand extreme positions.

With contact 8 of relay WIR in a right hand position, the miniature track switch point *ts* is actuated to a normal position in correspondence with the track switch TS in the field. Inasmuch as the switch machine lever SML is also in a normal position, an energizing circuit for the correspondence relay COR is completed from (+), through front contact 45 of relay WIR, wire 46, contact 47 of switch machine lever SML in a normal position, wire 48, polar contact 49 of relay WIR in a right hand position, wires 50 and 51, winding of relay COR, to (-). With the correspondence relay COR energized, the correspondence indicator CI is deenergized or unilluminated indicating to the operator that the track switch TS is in correspondence with the switch machine lever SML and the miniature track switch point *ts*.

With the control circuit of the relay WZ energized and with no trains upon the detector track circuit including the track relay T, the relay WZR is of course energized, thus completing an energizing circuit for the relay OS from (+), through front contact 52 of relay WZR, wires 53 and 54, winding of relay OS, to (-). With this energized condition of the relay OS, the indicator lamp I is deenergized or unilluminated indicating to the operator that the detector track section TK is not occupied.

With the signal control lever SGL in a center position as illustrated, thus deenergizing the signal relay SZ, the relays G are deenergized thereby energizing their respective relays M. More specifically, the relay 1M is energized from (+), through back contact 55 of relay 1AG, wire 56, back contact 57 of relay 1G, wire 58, windings of relay 1M, to (-); similarly, the relay 2M is energized from (+), through back contact 59 of relay 2G, wire 60, back contact 61 of relay 2AG, wire 62, windings of relay 2M, to (-).

With the relays SZ and SZR deenergized, the energizing circuit for the relay SIR is opened which maintains the indicator lamps EI and WI deenergized or unilluminated thereby indicating to the operator that the signals at the corresponding field station are at stop.

Let us assume that the operator desires to cause the track switch TS to be operated to a reverse extreme position. In accordance therewith he moves the switch machine lever SML to a reverse position operating contacts 22 and 47 to reverse dotted line positions. This opens the energizing circuit for the relay COR as contact 47 is then out of correspondence with the contact 49 of relay WIR. The deenergization of the relay COR energizes the indicator lamp CI from (+),

through back contact 63 of relay COR, indicator lamp CI, to (-).

With contact 22 of switch machine lever SML in a reverse position, negative potential is applied to the control circuit from the negative terminal of battery 15, through wires 70 and 71, contact 22 in a reverse position, wire 23, winding of relay WZR, wire 24, back contact 25 of relay SZR, control line wire 9, front contact 26 of track relay T, wire 27, windings of relay WZ, wires 28, 29 and 30, to the common return line and thence to the mid-point of battery 15. This application of negative potential to the switch machine control relay WZ causes its contacts to be operated to left hand dotted line positions, thereby causing the switch machine SM to be operated to a reverse extreme locked position in accordance with its control circuits as governed by the automatic approach locking and the like.

With the contact 33 of relay WZ out of correspondence with the contact 35 of relay WP during the operation of the track switch, the energizing circuit for the relay WIR is opened. Also, the operation of the switch machine SM and unlocking of the track switch TS deenergizes the relay WP further opening this energizing circuit for the relay WIR at front contact 37.

When the switch machine SM has accomplished the reverse operation so that the track switch TS is in a reverse position and locked, the relay WP is again energized but with the opposite polarity, thereby operating its polar contacts to left hand dotted line positions. With such reverse conditions established, an energizing circuit is completed for the relay WIR from the negative terminal of battery 16, through wires 72 and 73, polar contact 74 of relay WZ in a left hand position, wire 75, polar contact 35 of relay WP in a left hand position, wire 36, front contact 37 of relay WP, wire 38, back contact 39 of relay SZ, indicating line wire 11, back contact 40 of relay SZR, wire 41, windings of relay WIR, wires 42 and 43 to the common return line, wires 30 and 44, to the mid-point of battery 16. This application of negative potential to the relay WIR causes its polar contacts to be operated to left hand dotted line positions. With contact 8 in a left hand position, the miniature track switch point *ts* is operated to a reverse position in correspondence with the track switch TS in the field. Also, an energizing circuit is completed for the relay COR from (+), through front contact 45 of relay WIR, wire 46, contact 47 of switch machine lever SML in a reverse position, wire 16, polar contact 49 of relay WIR in a left hand position, wires 50 and 51, windings of relay COR, to (-). The energization of relay COR opens back contact 63 which deenergizes the correspondence indicator CI. Thus, the operator is assured that the track switch TS is actually in correspondence with the control lever SML and the miniature track switch points *ts*.

The operation of the track switch involved by the returning of the switch machine lever SML to a normal position, is merely the converse of the operation already described and need not be pointed out in detail.

The operator can cause traffic to pass over the track switch in an east or west direction with the track switch in either a normal or a reverse locked position. With the track switch in a normal position and locked, the operator may clear the signal I for traffic to move in an east bound direction by movement of the signal lever SGL to a right hand position; and similarly, he may

clear the signal 2 for traffic in a west bound direction by movement of the signal lever SGL to a left hand position. With the track switch TS in a reverse position and locked, the operator 5 may clear the signal 1A for traffic to move east onto the passing siding with the signal lever SGL in a right hand position; and similarly, he may clear the signal 2A for traffic to move west off the passing siding with the signal lever in a left hand position.

Assuming, for example, that it is desired to have a train move over the track switch TS in an east bound direction with the track switch in a normal position, the operator moves the signal 15 lever SGL to a right hand position. With the detector track section TK unoccupied, and the track switch TS in a normal position in correspondence with the switch machine lever SML and switch machine control relay WZ, then an energizing 20 circuit is completed for the relays SZ and SZR in series from the negative terminal of the battery 15, through wires 79 and 77, contact 78 of lever SGL in a left hand dotted line position, wire 79, winding of relay SZR, wire 80, front contact 81 25 of relay COR, control line wire 10, front contact 82 of track relay T, wire 83, front contact 84 of relay WP, wire 85, windings of relay SZ, wires 86, 29 and 30, to the common return line and thence to the control office to the mid-point of 30 battery 15.

Current flowing in this circuit causes the neutral contacts of the relay SZ to be actuated to energized positions and the polar contacts of relay SZ to be actuated to left hand positions (if not 35 already in such positions). These control conditions close the energizing circuit for the relay 1G from (+), through front contact 87 of relay WP, wire 88, polar contact 89 of relay WP in a right hand position, wire 90, front contact 91 of 40 relay SZ, wire 92, polar contact 93 of relay SZ in a left hand position, wire 94, front contact 95 of relay 1H, wire 96, windings of relay 1G, to (-). The energization of the relay 1G causes the red lamp of signal 1 to be extinguished and either the yellow or green lamps to be lighted in 45 accordance with traffic conditions in advance as selected through the home relay 1H. In this connection, it is to be understood that if a train is immediately in advance of the signal 1, then 50 the relay 1H will be deenergized and the energizing circuit for the relay 1G will not be completed through front contact 95 thereby causing the signal to give a red indication. With a train in the second block in advance of signal 1, the relay 1H will be energized with a certain polarity 55 causing the yellow indication of signal 1 to be selected; while with a train in the third block in advance of signal 1, the relay 1H will be energized with the opposite polarity thereby selecting 60 the green or least restrictive indication of the signal 1.

The energization of the relay 1G opens back contact 57 thereby deenergizing the relay 1M for the purpose of indicating in the control office the 65 clearing of signals in an east bound direction, as presently to be explained.

The energization of the relay SZR in the control office, closes a stick circuit for the correspondence relay COR from (+), through front 70 contact 97 of relay SZR, wire 98, front contact 99 of relay COR, wires 100 and 51, windings of relay COR, to (-). Thus, although the energizing circuit for the switch indicating relay WIR is open at back contact 40 of relay SZR and back 75 contact 39 of relay SZ, thereby deenergizing the

relay WIR and opening the pick-up circuit of relay COR at front contact 45; the relay COR is maintained energized through the stick circuit above pointed out.

It is noted that the control of the relay SZ is 5 not transmitted, or in other words its energizing circuit is opened, if the track switch TS is not in correspondence with the relay WZ and the control lever SML, as interpreted or indicated by the correspondence relay COR, by reason of front 10 contact 81. This would be true although the track switch happened to be in a particular extreme position and locked, but out of correspondence. If the track switch TS is unlocked or is in operation, the contact 84 of relay WP 15 is opened and the control of relay SZ is further prevented.

Also, the energization of the relay SZR opens the control circuit for the relay WZ at back contact 25 thereby preventing the operation of relay 20 WZ subsequent to the clearing of a signal, although its control lever SML might be moved to a new position. Thus, the operator may move his switch control lever SML to a new position subsequent to the movement of the signal lever SGL 25 to a clearing position so as to anticipate the next route to be lined up, and thereby cause the switch machine to operate the track switch TS to the new position immediately upon the passage of the first train beyond the detector track section TK. 30

The energization of the relays SZR and SZ completes an energizing circuit for the signal indicating relay SIR. As the relay 1G governs 35 east bound traffic and the relay 1M is deenergized, the relay SIR is energized with negative potential from the negative terminal of battery 16, through wires 72 and 101, back contact 102 of relay 1M, wire 103, front contact 104 of relay 2M, wire 105, front contact 39 of relay SZ, line wire 11, front contact 40 of relay SZR, wire 106, 40 windings of relay SIR, wires 107 and 43, to the common return line, wires 30 and 44, and thence to the mid-point of battery 16. Current flowing in this circuit through the windings of relay SIR actuates its neutral contacts to energized positions and its polar contacts to right hand positions. With the relay SIR thus energized, an energizing circuit for the indicator lamp EI is completed from (+), through front contact 108 45 of relay SIR, wire 109, polar contact 110 of relay 50 SIR in a right hand position, wire 111, indicator lamp EI, to (-). The illumination of this indicator informs the operator that traffic is established in an east bound direction.

The operator may cause the signal thus cleared 55 by the operation of the signal control lever SGL to be returned to stop by returning the lever SGL to a central position at any time he may desire, subject to such time locking, route locking or approach locking as may be included in the signal 60 control circuits in accordance with the requirements of practice, these particular features being omitted for the sake of clearness in explaining the present invention.

Although the relay WZR is deenergized by the 65 energization of the relay SZR, the relay OS is maintained energized through a circuit from (+), through back contact 52 of relay WZR, wire 112, front contact 113 of relay SZR, wires 114 and 54, windings of relay OS, to (-).

With any particular signal cleared, a train may accept such signal and pass over the track switch TS and in so doing shunt the detector track section TK thereby deenergizing the relay T. For example, with the signal 1 cleared, a train may 75

pass over the main track in an east bound direction deenergizing the relay T. The deenergization of the relay T opens the energizing circuit for the relays SZR and SZ, and also the energizing circuit of the relays WZR and WZ which is already opened at back contact 25. With this condition established, the relays WZR and SZR are both deenergized, and after a time period as determined by the slow releasing characteristics of the relay OS, the indicator lamp I is energized through a circuit from (+), through back contact 52 of relay WZR, wire 112, back contact 113 of relay SZR, wire 115, back contact 116 of relay OS, wire 117, indicator I, to (-). This condition maintains as long as the track relay T is deenergized. Upon the passage of the train, the relay SZR will again be energized if the operator has not returned the signal lever to stop thereby opening the energizing circuit for the indicator lamp I at back contact 113. On the other hand, if the signal lever SGL is returned to a stop position, then the relay SZR is left deenergized but the relay WZR is energized completing the pick-up circuit for the relay OS at front contact 52 and deenergizing the indicator I. The operator is thus informed that the train has passed beyond the detector track section TK.

The releasing period of relay OS is made of sufficient duration to allow the relays SZR and WZR to assume stabilized conditions before allowing the indicator I to be controlled in accordance with their positions.

The deenergization of the relays SZR and SZ upon deenergization of the track relay T, opens the energizing circuit of the relay SIR thereby opening the energizing circuit of the indicator lamp EI at front contact 108. This informs the operator that the signal I has gone to stop.

If the operator leaves the signal lever SGL in a cleared position for traffic in one direction or the other and does not move the switch machine lever SML to a new position, then trains may follow each other in accordance with regular spacing provided by the block signal system associated therewith in the field. However, if the operator moves the switch machine lever SML to a new position without returning the signal lever SGL to a stop or central position, the pick-up circuit for the relay COR would not be closed upon the deenergization of the relay SZR so that both the pick-up circuit and the stick circuit for the correspondence relay COR would be opened upon the passage of the first train. This would open the energizing circuit for the relay SZ preventing the signals clearing subsequent to the passage of the first train beyond the detector track section TK and allowing the relay WZ to be controlled thereby operating the switch machine and track switch TS to opposite extreme locked positions at which time the relay COR would be energized allowing the relay SZ to be controlled in accordance with the position of the signal lever SGL. This would allow train movements in a direction determined by the position of the lever SGL but over the route established with the track switch TS in the opposite position. From this it can be seen that the proper sequence of signal and switch operations are enforced by the system irrespective of the sequence of lever movements made by the operator.

Assuming traffic conditions to be established for movement in one direction or another over the track switch in either a normal or a reverse position, as previously described, with the signal control relay SZ energized either prior to a train

movement over the detector track section TK or subsequent thereto, the accidental unlocking of the track switch TS or its manual operation without consent of the centrally located operator, will be indicated in the control office and also cause the governing signals to go to stop. This is due to the front contact 84 of relay WP as included in the control circuits of the relay SZ. In other words, the deenergization of the relays SZR and SZ causes the indicating line 11 to be connected to the switch indicating relay WIR and the switch indicating contacts of the relays WP and WZ at any such time that the relay WP is deenergized. Such unauthorized operation of the track switch TS would cause the correspondence indicator CI 15 to be energized as the relay WIR in that case would be deenergized due to open front contact 37 of relay WP. This would inform the operator as to the condition of the track switch TS both by illumination of the indicator lamp CI and the 20 position of the miniature track switch point ts.

The present invention has thus provided an arrangement of circuits and devices whereby a track switch may be governed from a control office together with the associated signals which govern traffic over the four routes established by such track switch, through the medium of two polarized direct current circuits. Also, provision has been made whereby the same circuits may be utilized to indicate the occupancy of the detector track 25 section associated with the switch, and transmit such other conditions as will enable the condition and position of the switch together with the direction of traffic established by the signals to be indicated by polarized circuits including the 30 third line wire extending to the track switch from the control office. The polarized control circuits and the indication circuits employ three line wires with a common return line wire making a total of 35 four line wires for each track switch location, 40 with the option of employing the same common return line for each such location. The present invention provides these features in a safe and efficient manner.

Having thus shown and described a traffic controlling system as one rather specific embodiment of the present invention, it is desired to be understood that the particular embodiment of the invention illustrated has not been selected for the purpose of showing the scope of the invention or the exact construction preferably employed in practicing the invention, but has been selected for the purpose of facilitating in the disclosure of the underlying principles of the invention, and that various modifications, adaptations and additions may be made to adapt the invention to the particular problems encountered in practice, all without departing from the spirit or scope of the invention or the idea of means underlying the same, except as demanded by the scope of the 55 following claims.

What I claim is:—

1. In a switch and signal governing system, a distant track switch, signals associated with said track switch for governing traffic thereover, a signal control relay associated with said signals for selectively clearing a particular signal or causing all signals to remain at stop, a signal control line circuit connecting said signal control relay and a control office, means energizing said signal control relay to clear a particular signal, an indication line circuit extending from said track switch to said control office, switch indicating and signal indicating means located in said control office, switch indication control and 70 75

- signal indication control means at said switch, means including said switch indicating means and said switch indication control means in the same circuit through the medium of said indication line circuit when said signal control line circuit is deenergized, and means including said signal indicating means and said signal indication control means in a circuit through the medium of said indication line circuit when said signal control line circuit is energized.
2. In combination, a control office, a field station, a track switch at said field station, signals associated with said track switch to govern traffic thereover, three line circuits connecting said control office and said field station, means controlling operation of said track switch over one of said line circuits, means controlling the operation of said signals over another of said line circuits, means for indicating train occupancy of said track switch over said one and said another line circuits, means for indicating the position and locked condition of said track switch through the medium of said third and said another line circuits, and means for indicating the direction of traffic over said track switch through the medium of said third and said another line circuits.
3. In combination, a control office, a field station, a track switch at said field station, signals associated with said track switch to govern traffic thereover in both directions with said track switch in one or the other of two extreme locked positions, two line circuits connecting said control office and field station, means controlling said signals for determining the direction of traffic over said switch through the medium of one of said line circuits, means indicating the position and locked condition of the track switch through the medium of said other line circuit when said one line circuit is deenergized, and means indicating the direction of traffic over said track switch through the medium of said other line circuit when said one line circuit is energized.
4. In combination, a control office, a field station, a track switch at said field station, signals associated with said track switch to govern traffic thereover in both directions with said track switch in one or the other of two extreme locked positions a line circuit connecting said control office and said field station, a switch indicating relay at said control office at times governed in accordance with the position and locked condition of said track switch through the medium of said line circuit, a signal indicating relay at said control office at times governed in accordance with the direction of traffic over said track switch through the medium of said line circuit, and means determining at what times said switch and said signal indicating relays shall be respectively governed.
5. In a centralized traffic control system for railroads, a control office, a field station, a track switch at said field station, signals associated with said track switch, a switch control relay at said field station for governing the operation of said track switch, a line circuit connecting said control office and said field station for operating said switch control relay, a signal control relay at said field station, for governing the clearing of said signals to establish the direction of traffic over said track switch, another line circuit connecting said control office and said field station for operating said signal control relay, repeating relays included in series in said one and said another line circuits for indicating the condition of energization of the respective circuits, a third line circuit extending from said control office to said field station, a switch indicating relay at said control office governed in accordance with the position and locked condition of said track switch together with the correspondence between said track switch and said switch control relay through the medium of said third line circuit when said another line circuit is deenergized, a signal indicating relay at said control office governed in accordance with the direction of traffic established over said track switch through the medium of said third line circuit when said another line circuit is energized, and means deenergizing said another line circuit whenever said track switch is unlocked.
6. In combination, a railroad track switch, a switch machine for operating said track switch, a control lever for governing operation of said track switch, a control lever for governing operation of said signals, means indicating in said control office the correspondence between said control lever for said switch machine and said track switch when said signal control lever is in a position to prevent traffic over said track switch, and means storing the condition of said indicating means when said signal control lever is in a position to allow traffic over said track switch.
7. In a centralized traffic controlling system for railroads, a railroad track switch, a switch machine for operating said track switch, a switch control lever for governing operation of said switch machine, signals governing traffic over said track switch, a signal control lever for causing said signals to indicate clear or stop, means indicating the position and locked condition of said track switch, a correspondence relay for indicating correspondence between said track switch and said switch control lever, a pick-up circuit for said correspondence relay closed when said signals indicate stop and said track switch is in correspondence with said switch control lever, a stick circuit for said correspondence relay closed when said signals indicate clear, and means preventing said signals from indicating clear when said correspondence relay is deenergized.
8. In a centralized traffic controlling system for railroads, a railroad track switch, a switch machine for operating said track switch, a switch control lever for governing operation of said switch machine, signals governing traffic over said track switch, a signal control lever for causing said signals to indicate clear or stop, means indicating the position and locked condition of said track switch, a correspondence relay for indicating correspondence between said track switch and said switch control lever, a pick-up circuit for said correspondence relay closed when said signals indicate stop and said track switch is in correspondence with said switch control lever, a stick circuit for said correspondence relay closed when said signals indicate clear, means preventing said signals from indicating clear when said correspondence relay is deenergized, and an indicator lamp governed by said correspondence relay.
9. In a centralized traffic controlling system for railroads, a track switch, signals governing traffic over said track switch, signal control means for causing said signals to indicate stop, said means being manually operable to cause said signals to indicate clear, traffic controlled means for governing the indication of said signals, a line circuit for at times transmitting indications of the condition of said track switch and at other times transmitting indications of the condition

of said signals, and means including said signal control means for determining which indication shall be transmitted.

10. In a signal controlling system for railroads, the combination with a local control point and a distant signal, a signal control circuit for controlling said distant signal including a local relay and a distant relay in series, a line wire connecting said local control point and said distant signal location, and means for rendering said line wire available for one purpose when said local relay and said distant relay are energized and rendering it available for another purpose when said local relay and said distant relay are de-
10 energized.

11. In a railway traffic controlling system, the combination with distant traffic controlling device, a control circuit for controlling said distant traffic controlling device including a local relay and a distant relay in series, a line wire connecting said local control point and the point of said distant traffic controlling device, and means for rendering said line wire available for one purpose when said local relay and said distant relay are de-
20 energized and rendering it available for another purpose when said local relay and said distant relay are deenergized.

12. In a signal controlling system for railroads, the combination with a local control point and a distant signal, a signal control circuit for controlling said distant signal including a local relay and a distant relay in series, a line wire connecting said local control point and said distant signal location, and means including said local and distant relays for rendering said line wire available for one purpose when said control circuit is energized and rendering it available for another purpose when said signal control circuit is deenergized.

13. In a signal control system for railroads, the combination with a distant wayside point and a local office, a track switch and a signal at said distant wayside point, a circuit for controlling said signal including a local and a distant relay, and a second circuit including contacts of said local and said distant relay for indicating the condition of said signal when said local and said distant relays are energized and for indicating the position of said track switch when said local and said distant relays are deenergized.

14. In a signal control system for railroads, the combination with a distant wayside point and a local office, a track switch and a signal at said distant wayside point, a circuit for controlling said signal including a local and a distant relay, a line wire connecting said local office and said distant point, means for indicating the condition of said signal over said line wire only if said local and said distant relays are energized, and means for indicating the position of said track switch over said line wire only if said local and said distant relays are deenergized.

15. In a railway traffic controlling system, the combination with a distant track switch and a local tower, a lever in said tower for controlling said track switch, a signal for controlling traffic movements over said track switch, a stick relay having a pick-up circuit closed only if said lever and said track switch assume corresponding positions, and a stick circuit for said stick relay including a contact closed when said signal is manually controlled to display proceed for maintaining said relay energized irrespective of the movement of said lever.

16. In a railway traffic controlling system, the combination with a distant track switch and a local tower, a lever in said tower for controlling said track switch, a signal for controlling traffic movements over said track switch, a stick relay having a pick-up circuit closed only if said lever and said track switch assume corresponding positions, a stick circuit for said stick relay including a contact closed when said signal is manually controlled to indicate proceed, and a circuit for clearing said signal including a front contact of said stick relay.

5 combination with a distant track switch and a local tower, a lever in said tower for controlling said track switch, a signal for controlling traffic movements over said track switch, a stick relay having a pick-up circuit closed only if said lever and said track switch assume corresponding positions, a stick circuit for said stick relay including a contact closed when said signal is manually controlled to display proceed, and a circuit for clearing said signal including a front contact 10 of said stick relay.

17. In a railway traffic controlling system, the combination with a distant track switch and a local tower, a lever in said tower for controlling said track switch, a signal for controlling traffic movements over said track switch, a stick relay having a pick-up circuit closed only if said lever and said track switch assume corresponding positions, a stick circuit for said stick relay including a contact closed when said signal is manually controlled to indicate proceed, a circuit for clearing said signal including a front contact of said stick relay, and an indicator rendered active when said stick relay is deenergized.

20 18. In a railway traffic controlling system, the combination with a distant track switch and a local tower, a switch machine for controlling said track switch, a lever in said tower for controlling said switch machine, a signal for controlling traffic movements over said track switch, a stick relay having a pick-up circuit closed only if said lever and said track switch assume corresponding positions, a stick circuit for said stick relay including a contact closed when said signal is manually controlled to display proceed, a signal control circuit including a front contact of said stick relay, a switch machine control circuit for controlling said switch machine, a detector track relay associated with said track switch having a front contact included in each of said control 30 circuits, and an indicator displayed if both of said control circuits are deenergized at the same time.

35 19. In a railway traffic controlling system, the combination with a distant track switch and a local tower, a switch machine for controlling said track switch, a lever in said tower for controlling said switch machine, a signal for controlling traffic movements over said track switch, a stick relay having a pick-up circuit closed only if said lever and said track switch assume corresponding positions, a stick circuit for said stick relay including a contact closed when said signal is manually controlled to indicate proceed, a signal control circuit including a front contact of said stick relay, a switch machine control circuit for controlling said switch machine, a detector track relay associated with said track switch having a front contact included in each of said control 45 circuits, and an indicator displayed only when both of said control circuits are deenergized at the same time.

50 20. In a railway traffic controlling system, the combination with a distant track switch and a local tower, a switch machine for controlling said track switch, a lever in said tower for controlling said switch machine, a signal for controlling traffic movements over said track switch, a stick relay having a pick-up circuit closed only if said lever and said track switch assume corresponding positions, a stick circuit for said stick relay including a contact closed when said signal is manually controlled to indicate proceed, a signal control circuit including a front contact of said stick relay, a switch machine control circuit for 55 60 70 75

- controlling said switch machine available for use only if said signal control circuit is deenergized, a detector track relay associated with said track switch having a front contact included in each 5 of said control circuits, and an indicator displayed if both said control circuits are deenergized at the same time.
21. In a railway traffic controlling system, the combination with a distant track switch and a local tower, a switch machine for controlling said track switch, a lever in said tower for controlling said switch machine, a signal for controlling traffic movements over said track switch, a stick relay having a pick-up circuit closed only 10 if said lever and said track switch assume corresponding positions, a stick circuit for said stick relay including a contact closed when said signal is manually controlled to indicate proceed, a signal control circuit including a front contact of said stick relay, a switch machine control circuit for controlling said switch machine available for use only if said signal control circuit is deenergized, a detector track relay associated with said track switch having a front contact 15 included in each of said control circuits, a slow acting relay energized if said switch machine control circuit is energized, and an indicator displayed if both said control circuits are deenergized and said slow acting relay is assuming its 20 retracted position.
22. In a railway traffic controlling system, the combination with a distant track switch and a local tower, a switch machine for controlling said track switch, a lever in said tower for controlling said switch machine, a signal for controlling traffic movements over said track switch, a stick relay having a pick-up circuit closed only if said lever and said track switch assume corresponding positions, a stick circuit for said stick relay including a contact closed when said signal is 25 manually controlled to indicate proceed, a signal control circuit including a front contact of said stick relay, a switch machine control circuit for controlling said switch machine available for use only if said signal control circuit is deenergized, a detector track relay associated with said track switch having front contacts included in each 30 of said control circuits, a slow acting relay energized if either said switch machine control circuit or said signal control circuit is energized, and an indicator displayed if both said control circuits are deenergized and said slow acting relay is assuming its 35 retracted position.
23. In a railway traffic controlling system, the combination with a distant track switch having a signal associated therewith for controlling traffic over said switch and a local control office, of a switch machine for operating said track switch, a signal circuit for controlling said signal and including a series signal relay at said office, a switch control circuit for controlling said switch machine including a back contact of said signal relay so that said switch control circuit cannot 40 be energized while said signal circuit is energized, a series switch relay at said office in said switch control circuit, a detector track relay associated with said track switch and having two front contacts one included in each of said circuits, and an 45 indicator rendered effective if both said switch relay and said signal relay are deenergized.
24. In a system for electrically interlocking railway traffic controlling devices, a track switch operated by a switch machine, signals governing traffic over said track switch, a control relay for 50 controlling said switch machine, contacts controlled by said switch machine, a switch repeater relay arranged to indicate the position and correspondence of said contacts and said switch machine control relay, a correspondence relay energized only when said switch repeater relay and a lever for controlling said control relay assume corresponding positions, a signal control relay having an energizing circuit including contacts also controlled by said switch machine and contacts on said correspondence relay, and a stick circuit for said correspondence relay including contacts closed when said signal control relay is energized, whereby said signal control is subject to the correspondence of said switch control lever and said switch repeater relay only when said signal control relays are 55 deenergized.
25. In a system for electrically interlocking railway traffic controlling devices, a track switch operated by a switch machine, signals governing traffic over said track switch, a control relay for said switch machine, a manually operable lever controlling said switch machine control relay, lockout means for preventing the operation of said switch machine, a switch repeater relay arranged to check the correspondence of said switch machine and said switch machine control relay, a correspondence relay arranged to check the correspondence of said switch repeating relay and said switch control lever, a signal control relay having an energizing circuit which includes contacts on said switch repeater relay and contacts on said correspondence relay, and a stick circuit for said correspondence relay closed when 60 said signal control relay is energized.
26. In combination, a railway system including a track switch, a switch machine for operating said track switch, a lever for controlling said switch machine, lock-out means for preventing operation of said switch machine in response to a change in the position of said lever, a correspondence relay energizable only when said lever and switch machine assume corresponding positions, a signal for governing traffic over said track switch, a signal device which is energized whenever said signal is caused to display a proceed indication, a circuit for energizing said signal device including a front contact of said correspondence relay, and a second circuit for said correspondence relay including a contact of said signal device closed only when said signal device is energized, whereby correspondence between said lever and switch machine is necessary only during the act of clearing of said signal.
27. In combination, a railway system including a track switch, a switch machine for operating said track switch, a lever for controlling said switch machine, lock-out means for preventing operation of said switch machine in response to a change in the position of said lever, a signal for governing the movement of traffic over said track switch, and a clearing circuit for said signal which can only be completed if said switch machine and said lever assume corresponding positions but which if once completed remains closed independently of such correspondence between said switch machine and lever.
28. In combination, a track switch, a switch machine for operating said track switch, a control relay for controlling said switch machine, a signal for governing movement of traffic over said track switch, and a clearing circuit for said signal which may be closed only if said track switch and its control lever assume corresponding positions but 75

which if once closed will remain closed independently of such correspondence between said switch machine and its control lever.

29. In combination, a track switch, a switch machine for operating said track switch, a signal for governing movement of traffic over said track switch, lock-out means for preventing operation of said switch machine when said signal is clear, and a clearing circuit for said signal which may be closed only if said track switch and its control lever assume corresponding positions but which if once closed will remain closed independently of such correspondence between said switch machine and its control lever, whereby operation of said control lever to a new switch controlling position when said signal is clear will not effect a change in either said switch machine or said signal.

30. In combination, a track switch, a switch machine for operating said track switch, a signal for governing movement of traffic over said track switch, lock-out means for preventing operation of said switch machine when said signal is clear or traffic conditions are unfavorable, and a clearing circuit for said signal which may be closed only if said track switch and its control lever assume corresponding positions but which if once closed will remain closed independently of such correspondence between said switch machine and its control lever, whereby operation of said control lever to a new switch controlling position when said signal is clear will not effect a change in either said switch machine or said signal.

31. In combination, a track switch, a switch machine for operating said track switch, a signal for governing movement of traffic over said track switch, lock-out means for preventing operation of said switch machine when said signal is clear or a detector track circuit associated with said track switch is occupied, and a clearing circuit for said signal which may be closed only if said track switch and its control lever assume corresponding positions but which if once closed will remain closed independently of such correspondence between said switch machine and its control lever, whereby operation of said control lever

to a new switch controlling position when said signal is clear will not effect a change in either said switch machine or said signal.

32. In combination, a track switch operated by a switch machine, a free and non-lockable lever for governing the operation of said track switch, switch position indicating means, a correspondence relay capable of being picked up when and only when said lever and said switch position indicating means are in corresponding positions, an energizing circuit for traffic controlling means capable of being closed when and only when said correspondence relay is energized, and a stick circuit for said correspondence relay capable of being closed when and only when said energizing circuit is closed.

33. In combination; a track switch operated by a switch machine; a free and non-lockable lever for governing the operation of said track switch; a signal for governing traffic over said track switch; a clearing circuit for said signal, which may be manually closed only when said track switch and said control lever assume corresponding positions, but which, if once closed, will remain closed independently of such correspondence between said track switch and said control lever unless manually or automatically opened; means preventing response of said track switch to said control lever when said clearing circuit is closed; and means automatically opening said clearing circuit upon a passage of a train over said track switch.

34. In combination, a track switch, a switch machine for governing operation of said track switch, a control lever governing operation of said switch machine, signals governing traffic over said track switch capable of being caused to indicate proceed only when correspondence exists between said control lever and said track switch, locking means preventing operation of said switch machine when one of said signals is at proceed, and means preventing the movement of said control lever from effecting a change in the condition of said one signal when that signal is at proceed.
